UNITED STATES PATENT OFFICE.

WILLIAM BELL ROHMER, OF BAY ST. LOUIS, MISSISSIPPI.

MAIL-POUCH CATCHING AND DELIVERING MECHANISM.

SPECIFICATION forming part of Letters Patent No. 766,731, dated August 2, 1904.

Application filed September 22, 1903. Serial No. 174,204. (No model.)

To all whom it may concern:

Be it known that I, WILLIAM BELL ROHMER, a citizen of the United States, residing at Bay St. Louis, in the county of Hancock and State 5 of Mississippi, have invented a new and useful Mail-Pouch Catching and Delivering Mechanism, of which the following is a specification.

This invention relates to that class of mail- 10 pouch catching and delivering mechanism set forth in a previous patent granted to me on August 12, 1902, numbered 707,017. While there are various features presented in the present case that are covered by the claims of 15 said patent, there are certain features herein that are improvements over the structure therein illustrated.

One of the objects of this invention is to improve the mechanism employed alongside 20 the track, said mechanism securely holding the pouch to be delivered to the car mechanism and receiving the pouch therefrom.

A further object is to provide means which will automatically lock the pouch so received 25 on the mechanism and will carry it away from the zone of passing trains.

Still another object is to provide means which will permit the detachment of pouches 30 when placed upon the wrong side of the mechanism or caught by a train running in the wrong direction, thereby avoiding serious damage which would otherwise be almost certain to occur.

The preferred form of construction is illustrated in the accompanying drawings, wherein—

Figure 1 is a perspective view of the car and track-side mechanism just prior to the exchange of sacks. Fig. 2 is also a perspective view after the exchange has taken place. Fig. 3 is a horizontal sectional view through the supporting means. Fig. 4 is a detail vertical sectional view through one end of one of the upper arms. Fig. 5 is a detail horizontal 45 sectional view through a portion of the locking means and indicating the manner in which said locking means is released should the pouch be caught by a train running in the wrong direction. Fig. 6 is a detail view illustrating a slight modification of the construction shown in Fig. 5.

Similar reference-numerals indicate corresponding parts in all the figures of the drawings.

The car mechanism is substantially like that 55 illustrated in Fig. 5 of the aforementioned patent and may be briefly described as follows: A horizontally-disposed rod 10 is journaled in suitable keepers 11, located at one side of the doorway, and carries at one end an inwardly-extending handle 12 and an outwardly-extending arm 13, said arm being provided with a cross-bar 14, having retaining-lips 15, preferably formed by the terminals of a rod 16, secured longitudinally upon the cross-bar 14. 60 This rod is of suitable metal that will bend with comparative ease. A keeper is employed for preventing the detachment of the bag transferred to the arm. This keeper comprises a pair of spaced sleeves 17, slidably mounted 65 upon the arm and connected by webs 18, the outer sleeve being provided with angularly-formed fingers 19, the free ends of which are movable into and out of coacting relation with the cross-bar 14 when the sleeves are moved 70 upon the arm. This movement is attained by means of a coiled spring 20, surrounding the rear portion of the arm 13 and bearing against projections 21, secured to the rearmost sleeve. Said sleeve is preferably provided with a pair 75 of upstanding spaced ears 22, between which is arranged to fit another ear 23, mounted upon the arm, when the sleeves are moved rearwardly against the tension of the spring 20. Said ears when so aligned are adapted to 80 receive a holding-pin 24, comprising pivoted sections, one of which is passed through the ears, the other being attached to a suitable strap or cord 25, that is placed about the center of the pouch 26. This pouch is provided 85 at one end with a comparatively large ring 27, which is engaged beneath the rear retaining-lip 15 and upon the rear end of the cross-bar 14.

So far as thus described, with the exception 90 of the holding-pin 24, the mechanism is substantially the same as that set forth in my former patent, and with the exception of said pin no claim is herein made to this structure.

The track-side mechanism is preferably constructed as follows: A pair of spaced supporting-standards 28 are located at a suitable 100

point alongside the track and carry at their upper ends suitable plates 29, constituting hinge-ears between and to which are pivoted upwardly-swinging independent arms 30, one 5 of said arms being located at the top of each standard. The arms extend in rear of the standards and are provided with counterweights 31, which will insure the elevation of their operative ends. Said ends are provided 10 with depending plates 32, to the lower ends of which are pivoted depending supporting-hooks 33, the shanks of which extend above the pivots and constitute weights which will swing the hooks to an upright position, as indicated by dotted lines in Fig. 4. These 15 hooks are oppositely disposed. Extending between the standards 28, below the arms 30, is another arm 34, which has an intermediate outstanding pin 35, journaled in the standards. The thickness of this arm 34 is less 20 than the distance between the standards, and said arm is permitted to move transversely in the space, but is normally held centered by means of coiled springs 36, surrounding the 25 journal-pin and interposed between the arm and standards. The rear end of the arm 34 is formed into a suitable handle, while the opposite end carries a cross-bar 37, having on its upper face retaining-lips 38, formed by 30 the ends of an easily-bendable rod 39, secured longitudinally upon the cross-bar. The terminals of this cross-bar coact, respectively, with the independently and upwardly swinging arms 30, as is hereinafter more fully described. 35 This arm 34, with its cross-bar, constitutes both a delivering and receiving arm for the pouches.

An automatic lock is mounted upon the arm 34 and comprises spaced sleeves 40, connected by webs 41, the foremost sleeve having angularly-disposed keeper-fingers 42, that coact with the cross-bar 37. A spring 43 urges the fingers into such coacting relation, and they may be held rearwardly and in 45 spaced relation thereto by means of eyes 44, mounted, respectively, on the arm and the rear sleeve, which eyes are adapted to aline and receive a pin 45, that is composed of pivotally-connected sections, one of which is 50 adapted to be passed through the eyes, while the other is secured to the pouch. The arm 34 swings downwardly, but can be held in horizontal position by either of a pair of sliding bolts 46, which are mounted, respectively, on the standards 28 and are slideable 55 above and into the path of movement of the arm 34, these bolts being mounted in guide-boxes 47.

It is believed that the operation of the apparatus will be clearly apparent. The clerk upon the train places the pouch to be delivered therefrom upon the car mechanism, as illustrated in Fig. 1, the ring 27 being suspended from the rearmost terminal of the 65 cross-bar 14, the lock being retracted and

held by the pin 24, passed through the alined ears in a rearwardly direction. The pouch to be delivered to the car is placed in position in the following manner: The lower arm 34 is elevated to a horizontal position and locked 70 by the bolt 46, disposed on the side nearest the approaching train. The arm 30, located away from the approaching train, is lowered, and the ring 27^a of the mail-pouch is supported by the hook 33 and the rearmost retaining-lip. The lock of the track-side mechanism is retracted and locked by the pin 45, secured to the central portion of this pouch, said pin being passed through the ears from the side opposite the approaching train. As 80 the mail-car passes the track-side mechanism the foremost terminal of the cross-bar 14 will pass through the ring 27^a, while the front terminal of the cross-bar 37 will pass through the ring 27. Consequently the bags will be 85 transferred from one mechanism to the other. Immediately the pins will be withdrawn from the ears, thereby releasing the locks, which will under the impulse of the springs be projected to operative positions, thereby locking 90 the exchanged sacks upon the mechanisms. The shock imparted to the arm 34 will, moreover, cause said arm to move laterally against the tension of the opposing spring and sufficiently to release it from the bolt 46, 95 that is holding it in horizontal position. Thereupon said arm 34 will drop, carrying the caught bag downwardly and out of dangerous proximity to passing trains. Should the pouch be placed upon the wrong side of the 100 track mechanism, it will be caught by the catcher on the car and removed without seriously injuring the apparatus. This will be evident when it is considered that the hooks 105 33 will readily turn, as indicated in dotted lines in Fig. 4, while the retaining-lips 38 will simply bend backwardly. The pin 45 will also be withdrawn from the ears, as will be apparent by reference to Fig. 5. The outer section, bending backwardly and engaging 110 the adjacent ear, will turn upon the same as a fulcrum, thereby withdrawing the inner section from the ears.

It will thus be seen that a structure is provided which will operate efficiently and will 115 exchange pouches without injuring them or their contents. Moreover, the pouches after being transferred are securely locked to the mechanism, so that there is no danger of their dropping beneath the car-wheels. A still 120 further advantage resides in the means which will permit the taking of sacks by trains running in the wrong direction without materially injuring the apparatus.

Instead of employing the ears 22 and 23, 125 (shown in Figs. 1 to 5, inclusive,) ears or flanges 48 and 49 may be provided. These ears or flanges are provided with open eyes or seats for the reception of the pin 50, which may be readily disengaged from the open eyes or seats 130

by a strain or pull in either direction. This construction will obviate the necessity of employing the lever 24. (Shown in Fig. 5 of the drawings.)

5 From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

15 Having thus described my invention, what I claim as new, and desire to secure by Letters Patent, is—

1. In apparatus of the class described, the combination with a support, of independent pouch-engaging arms mounted on the support, and another arm coacting with either of the independent arms in supporting a pouch.

2. In apparatus of the class described, the combination with a support, of independent pouch-engaging arms pivotally mounted on the support, and another arm also pivoted on the support and coacting with either of the independent arms in supporting a pouch.

3. In apparatus of the class described, the combination with swinging pouch-engaging arms having independent upwardly-swinging movements, of a downwardly-swinging pouch-engaging arm coacting with either of the upwardly-swinging pouch-engaging arms.

35 4. In apparatus of the class described, the combination with separately-supported pouch-engaging arms, of another arm having a cross-bar, the terminals of which coact respectively with each of the separate arms.

40 5. In apparatus of the class described, the combination with a support, of swinging pouch-engaging arms mounted on the support having independent movements, and a downwardly-swinging pouch-engaging arm jour-

45 naled on the support beneath the independent arms and having a cross-bar, the terminals of which coact respectively with each of the independent arms.

6. In apparatus of the class described, the combination with separately-supported pouch-engaging arms, of another arm having a cross-bar, the terminals of which coact respectively with each of the separate arms, and pouch-engaging means carried by the terminals of

55 the cross-bar and the arms.

7. In apparatus of the class described, the combination with spaced standards, of independent arms mounted on the standards, and another arm mounted between the standards 60 and having a cross-bar coacting with the independent arms.

8. In apparatus of the class described, the combination with spaced standards, of independent upwardly-swinging arms mounted 65 upon the upper ends of the standards, and

another arm journaled to and between the standards below the upper arms and having a cross-bar, the terminals of which coact respectively with the upwardly-swinging arms.

9. In apparatus of the class described, the combination with spaced supports, of an arm journaled between the supports and having a transverse movement therebetween, means for yieldingly holding the arm against such movement, and a lock mounted on one of the supports and movable into the path of movement of the arm. 70

10. In apparatus of the class described, the combination with spaced supports, of an arm journaled to and between the supports and having a transverse movement therebetween, springs interposed between the supports and arm, and separate locks movably mounted on the supports and arranged to coact with the arm. 80

11. In apparatus of the class described, the combination with spaced standards, of an arm extending between the standards and having an outstanding journal mounted on said standards, coiled springs surrounding the journal 90 on opposite sides of the arm and bearing against the inner faces of the standards, and bolts slidably mounted on the standards and movable into the path of movement of the arm. 95

12. In apparatus of the class described, the combination with coacting pouch-delivering arms, one of which also constitutes a pouch-receiving arm, and an automatic lock movably mounted on the pouch-receiving arm and 100 arranged to prevent the detachment of a pouch received thereon.

13. In apparatus of the class described, the combination with an upwardly-swinging pouch-delivering arm, of a downwardly-swinging pouch-delivering and receiving arm, and an automatic lock movably mounted on the pouch-receiving arm for preventing the detachment of a pouch received thereon. 105

14. In apparatus of the class described, the combination with independent upwardly-swinging pouch-delivering arms, of a downwardly-swinging pouch-delivering and receiving arm having a cross-bar that coacts with the independent arms, and a lock mounted 110 on the downwardly-swinging arm and having portions that coact with the cross-bar to prevent the detachment of pouches received thereon. 115

15. In apparatus of the class described, the combination with a supporting-arm, of a depending pouch-supporting hook pivoted to the end thereof, and means for automatically reversing the hook when a pouch has been removed therefrom. 120

16. In apparatus of the class described, the combination with a supporting-arm, of a depending hook having an upstanding weighted shank pivoted between its ends to the arm, the portion of said shank on the side of the 130

pivot opposite the hook overbalancing said hook and causing the same to automatically reverse when the pouch has been removed therefrom.

- 5 17. In apparatus of the class described, the combination with a pouch-receiving arm, of an automatic lock mounted thereon, and a holding-pin for the lock comprising jointed sections.
- 10 18. In apparatus of the class described, the combination with a pouch-receiving arm having an eye, of an automatically-operating lock slidably mounted on the arm and having

an eye arranged to align with the eye thereof, and a holding-pin for the lock comprising 15 pivotally-connected sections, one of said sections engaging in the aligned eyes, the other being adapted to be secured to a pouch.

In testimony that I claim the foregoing as my own I have hereto affixed my signature in 20 the presence of two witnesses.

WILLIAM BELL ROHMER.
